Primary Examiner — Holly H Bayham(74) Attorney, Agent, or Firm — Fross Zelnick Lehrman & Zissu, P.C.; Lawrence E. Apolzon, Esq.(57) CLAIM

The ornamental design for a decorative element for handbag, as shown and described.

DESCRIPTION

FIG. 1 is a front perspective view of a decorative element for handbag showing my new design;

FIG. 2 is a right side view thereof;

FIG. 3 is a left side view thereof;

FIG. 4 is a front view thereof;

FIG. 5 is a back view thereof;

FIG. 6 is a top view thereof;

FIG. 7 is a bottom view thereof;

FIG. 8 is a front perspective view of the decorative element shown in FIG. 1, shown in a different position relative to the handbag;

FIG. 9 is a right side view thereof;

FIG. 10 is a left side view thereof;

FIG. 11 is a front view thereof; and,

FIG. 12 is a back view thereof.

The broken line showing of portions of the body of the bag, chain, and ring in the drawings shows unclaimed subject matter.

1 Claim, 9 Drawing Sheets(56)
